[57] CLAIM

The ornamental design for a bidet, as shown and described.

DESCRIPTION

FIG. 1 is a perspective view taken from the top, front and right side of a bidet showing our new design;

FIG. 2 is a top plan view thereof;

FIG. 3 is a right side elevational view thereof, the left side being a mirror image of the right side shown;

FIG. 4 is a front elevational view thereof; and

FIG. 5 is a rear elevational view thereof.

The broken line representations of overflow drain holes in FIG. 1, fixture mounting holes in FIGS. 1 and 2, and an access panel in FIG. 3 are for the purpose of illustration only.

FIG. 1

FIG. 2

FIG. 3

FIG. 4

FIG. 5
